(57) CLAIM

The ornamental design for a storage enclosure, as shown and described.

DESCRIPTION

FIG. 1 is a front view of the storage enclosure embodying the new design.

FIG. 2 is a rear view thereof.

FIG. 3 is a top view thereof.

FIG. 4 is a bottom view thereof.

FIG. 5 is a right side view thereof; and,

FIG. 6 is a left side view thereof.

1 Claim, 5 Drawing Sheets
